UNITED STATES PATENT OFFICE.

JOHANN G. WALLMANN, OF OAKLAND, CALIFORNIA.

ELECTRIC HEATER AND STERILIZER.

987,658.

Specification of Letters Patent. Patented Mar. 21, 1911.

Application filed November 8, 1909. Serial No. 526,919.

To all whom it may concern:

Be it known that I, JOHANN G. WALLMANN, a citizen of the United States, residing at Oakland, in the county of Alameda and State of California, have invented certain new and useful Improvements in Electric Heaters and Sterilizers, of which the following is a specification.

My invention relates to improvements in electric heaters and sterilizers.

The object of my invention is to provide a device for heating and sterilizing fluid, such as water, by means of electricity which requires a minimum current for such purpose, wherein elements are used which are non-destructible by electric action, in which when the device is removed from water no further consumption of current occurs, and which device can be handled at all times when in use without injury to the hands, the said device being particularly advantageous for sterilizing and precipitating the foreign elements in the water.

My improved device consists in the construction, arrangement and combination of parts shown in the accompanying drawings, described in the following specification and pointed out in the appended claims.

Referring to the accompanying drawings which illustrate my invention, Figure 1 is a sectional view of my said device. Fig. 2 is a side view of the same. Fig. 3 shows a sectional plan view and also a central longitudinal sectional view of the carbon disks A and B hereinafter described, and Fig. 4 represents a sectional plan view of the porcelain ring C hereinafter mentioned and also a central longitudinal sectional view of the same.

In the figures, A and B represent electrodes of opposite polarity fed by the rubber covered stranded wires 50 and 51. Porcelain rings to hold the carbon disks in position are shown at C, and O indicates a porcelain frame containing said disks and rings.

F shows a groove on each side of the porcelain frame O to allow space for screws E and small connecting bus bars D.

H indicates a groove filled with non-conducting insulating material to prevent parts D and E and wires 50 and 51 grounding on cylinder L, which cylinder is designed for containing the parts therein shown.

G shows a small check valve screwed into 55 the porcelain frame O, being in alinement with the passage V.

Chambers between the disks A and B to allow electrical action on water therein are shown at N. Perforations M are inlets and 60 outlets for the passage of water into and from the cylinder L as acted on by the elements therein contained.

J is a handle preferably of wood for handling the device.

I shows a suitable tube in the handle for the wires 50 and 51, the said tube being preferably soldered to cylinder L and flared at the top to hold the handle firmly in position.

Parts P represent small clips soldered to cylinder L to hold frame O in position.

To operate the device shown in Fig. 1, it is set in a vessel containing water, the same entering perforations M in the cylinder L 75 and thence passing through top and bottom channels and the chambers N. When the water is contained in the chambers electrical action between elements A and B causes the water to heat in said chambers, thereupon 80 impelling it upward, and it being held in check from downward movement by check valve G. The warm water and steam thereupon rising, releases check valve G and allows cold water in the bottom of the cylinder L to ascend into chambers N, repeating the said operation of heating, a circulation being effected by cold water rising from the bottom, the hot water being displaced.

The device may be used on voltages varying from 250 to 100 volts without changing the distances between electrodes. In said device platinum plated metal disks may be used instead of carbon disks, or any suitable conducting material that may stand the 95 electrical action while placed in the water.

Having thus described my invention what I claim as new and desire to secure by Letters Patent is:—

1. In a device of the character described 100 the combination of a vessel having top and bottom openings, a handle for said vessel having a longitudinal passage extending therethrough, a cup-shaped frame having a bottom opening centrally supported in said vessel, a plurality of electrodes of opposite polarity having central openings in alinement with said bottom opening alternately 105

spaced therein, and current-conducting means leading through said handle and to said elements respectively.

2. In a device of the character described 5 the combination of a vessel having top and bottom openings, a handle for said vessel having a longitudinal passage extending therethrough, a cup-shaped frame having a bottom opening provided with a valve centrally supported in said frame, a plurality 10 of electrodes of opposite polarity having central openings in alinement with said bottom opening alternately spaced therein, and current conducting means leading through 15 said handle and to said elements respectively.

3. In a device of the character described 20 the combination of a vessel having top and bottom openings, a recessed frame having a bottom opening provided with a valve centrally supported in said frame, a plurality of electrodes of opposite polarity having central openings in alinement with said bottom opening alternately spaced therein, and current-conducting means leading to said 25 elements respectively.

In testimony whereof I affix my signature, in presence of two witnesses.

JOHANN G. WALLMANN.
